UNITED STATES PATENT OFFICE.

FRANK J. BISCHOF, OF DETROIT, MICHIGAN.

CURTAIN-POLE.

1,233,835.

Specification of Letters Patent. Patented July 17, 1917.

Application filed January 25, 1917. Serial No. 144,405.

To all whom it may concern:

Be it known that I, FRANK J. BISCHOF, a citizen of the United States, and a resident of Detroit, in the county of Wayne and State 5 of Michigan, have invented a new and Improved Curtain-Pole, of which the following is a full, clear, and exact description.

My invention has for its object to provide a pole having curtain-supporting means 10 which permit the ready adjustment of the curtain relatively to the pole. The curtain supporting means consists of hangers which extend through a slot in a guide, the hangers within the guide having each an opening 15 in which a bearing ball is disposed, the bearing ball engaging the inner side of the guide. The guide is disposed in a casing having a slot through which the hangers extend, an operating cord which extends in the casing 20 being adjustably secured to certain of the hangers.

Additional objects of the invention will appear in the following specification, in which the preferred form of the invention is 25 disclosed.

In the drawings similar reference characters denote similar parts in all the views, in which—

Figure 1 is a longitudinal sectional view 30 of my curtain pole;

Fig. 2 is an enlarged sectional view similar to that shown in Fig. 1;

Fig. 3 is a sectional plan view of the curtain pole;

Fig. 4 is an enlarged sectional view on the line 4—4 of Fig. 2;

Fig. 5 is an enlarged sectional view on the line 5—5 of Fig. 2;

Fig. 6 is an enlarged sectional view on the line 6—6 of Fig. 2;

Fig. 7 is an enlarged sectional view on the line 7—7 of Fig. 2; and

Figs. 8 and 9 are enlarged sectional views 45 illustrating the means for securing the hangers to the operating cord.

By referring to the drawings, it will be seen that a guide 10 is provided, this guide 10 having a groove 11 in its top and a slot 12 in its bottom. Secured to the guide 10 50 and spaced apart there are disks 13 which engage the inner sides of a casing 14 in which the guide 10 is disposed. This casing 14 has a slot 15 at its bottom. The disks 13 are cut away at 16 from the slot 12 in the 55 guide 10, to the slot 15 in the casing 14.

There are inner flanges 17 at the sides of the slot 15 for engaging the lower portions of the disks 13 to prevent the rotary movement of the disks with the guide 10 relatively to the casing 14.

60

Extending upwardly through the slots 15 and 12 there are hangers 18, the said hangers 18 having ring portions 19 disposed in the guide 10, a bearing ball 20 being disposed in each of the ring portions 19, these 65 bearing balls 20 being sufficiently wide to prevent their movement through the slot 12, so that the bearing balls 20 will prevent the downward movement of the hangers 18 and will also assist in the ready movement of 70 the hangers 18 along the casing 14 when such movement is desired.

Two of the adjacent hangers 18 are provided with means by which they may be secured to the operating cord 21. As will be 75 seen by referring to Figs. 1, 2 and 3 of the drawings, these last mentioned hangers are preferably disposed next to each other, and are indicated at 18^a. Each of the hangers 18^a has a member 22 with two guide ways 23

80

and a threaded orifice 24, each hanger 18^a also having a second member 25 with two guide members 26 and guideways 27, 27^a and 27^b in which a screw 28 is disposed, the thread of this screw meshing in the threaded orifice 24 so that the screw 28 may be turned 85

85

to press the screw head 28^a against the lower portion of the member 25 and thereby move the clamp member 29 on the member 25 in the direction of the clamp member 30 on the member 22, the said clamp members 29 and 30 clamping the operating cord 21. Inasmuch as the heads 28^a of the screws 28 extend below the slot 15 it 90 will be understood that the screws 28 may be actuated to free the hangers 18^a from the operating cord 21 to permit of the adjustment of the hangers 18^a relatively to the operating cord 21. After adjustment the hangers 18^a may be again secured to the operating cord by means of the clamping members 29 and 30 and the screw 28. The bottom of each of the hangers 18 and 18^a are fashioned into a ring 31 for engagement by 95

the curtain pins 33 which are secured to a curtain 34 in the customary manner.

90

Disposed around the lower portion of the end 31 of the guide 10 there is a U-shaped member 35, and disposed around the lower portion of the end 36 of the guide 10 there 100

105

110

is another U-shaped member 35, the sides of the lower portions of these U-shaped members 35 being upwardly at 37 against the outer sides of the guide 10 to prevent the guide from spreading apart and thereby abnormally opening the slot 15. Below the U-shaped member 35 at the end 31 of the guide 10 there is a pulley 38 disposed on a vertical axis the pulley 38 being spaced from the U-shaped member 35 by a block 39. The operating cord 21 is disposed around the pulley 38 and is held in place by a keeper 40 which has its base 41 disposed over the U-shaped member 35, the keeper 40, the U-shaped member 35 and the block 39 being held in place relatively to the guide 10 by a bolt 42 on which the pulley 38 is mounted. A bracket 43 is disposed below the U-shaped member 35 at the other end of the guide 10 and is spaced from the said U-shaped member 35 by a block 44 the said U-shaped member 35, the block 44 and the bracket 43 being held in place relatively to the guide 10 by a bolt 45.

25 The operating cord 21 at one side of the pulley 38 is secured to one of the hangers 18^a and at the other side of the pulley 38 the operating cord 21 is secured to the other hanger 18^a. The two ends of the operating cord 21 are then disposed one over each of the pulleys 46 which are journaled on a horizontal axis to the bracket 43, the ends 40 of the operating cord 21 passing down through an opening 47 at the bottom of the casing 14. By pulling one of the ends 48 of the operating cord 21, the hangers 18^a will be moved away from each other and in the direction of the ends of the casing 14, and by engagement of the hangers 18 with the hangers 18^a the hangers 18 between the hangers 18^a and the ends of the casing will be moved with the hangers 18^a in the direction of the ends of the casing. When the other end 48 of the operating cord 21 is pulled downwardly it will move the hangers 18^a in the direction of each other, and the hangers 18^a will draw the curtain, which will pull the hangers 18 to the desired supporting positions.

50 Having thus described my invention, I claim as new, and desire to secure by Letters Patent:

1. In a curtain pole, a guide having a longitudinal slot in its bottom, a hanger having a bearing extending through the slot, and a bearing ball disposed in the bearing and engaging the inner side of the guide.

2. In a curtain pole, a guide having a longitudinal slot, a hanger extending through the slot and having a bearing ring disposed in the guide, and a bearing ball disposed in the ring and engaging the inner side of the guide, for the purpose specified.

3. In a curtain pole, a guide having a longitudinal groove in its top and a longi-

tudinal slot in its bottom, a hanger extending through the slot and having a bearing ring disposed in the guide with the edge of the hanger in the groove, and a bearing ball disposed in the bearing ring and engaging the inner side of the guide for the purpose specified.

4. In a curtain pole, a guide having a longitudinal slot in its bottom, a hanger having a bearing extending through the slot, a bearing ball disposed in the bearing and engaging the inner side of the guide; a casing in which the guide is disposed, and disks secured to the guide and engaging the casing for spacing the guide from the casing; the disks having cut away portions in which the hanger extends.

5. In a curtain pole, a guide having a longitudinal slot in its bottom, a hanger having a bearing extending through the slot, a bearing ball disposed in the bearing and engaging the inner side of the guide, a casing in which the guide is disposed and having a longitudinal slot at its bottom out of which the hanger extends, disks secured to the guide and engaging the casing; the disks having openings extending from the slot in the guide to the slot in the casing.

6. In a curtain pole, a guide having a longitudinal slot in its bottom, a hanger having a bearing extending through the slot, a bearing ball disposed in the bearing and engaging the inner side of the guide, a casing in which the guide is disposed and having a longitudinal slot at its bottom with inner flanges extending from the sides of the slot, the hanger extending in the casing slot, disks secured to the guide and engaging the casing, the disks having openings extending from the slot in the guide to the slot in the casing, and the disks at the sides of the openings engaging the flanges.

7. In a curtain pole, a guide having a longitudinal slot in its bottom, a hanger having a bearing extending through the slot, a bearing ball disposed in the bearing and engaging the inner side of the guide, a casing in which the guide is disposed and having a longitudinal slot at its bottom out of which the hanger extends, disks secured to the guide and engaging the casing; the disks having openings extending from the slot in the guide to the slot in the casing, a pulley at one end of the guide, and a cord to which the hanger is secured, disposed around the pulley and in the openings in the disks.

8. In a curtain pole, a guide having a slot in its bottom, a casing in which the guide is disposed and having a slot in its bottom, disks secured to the guide and engaging the inner sides of the casing to hold the guide in position relatively to the casing, the disks having cut away portions from the slot in the guide to the slot in the casing, hangers extending in the slots and in the cut away

portions in the disks, and means for supporting the hangers.

9. In a curtain pole, a guide having a slot in its bottom, a casing in which the guide is disposed and having a slot in its bottom, disks secured to the guide and engaging the inner sides of the casing to hold the guide in position relatively to the casing, the disks having cut away portions from the slot in the guide to the slot in the casing, hangers extending in the slots and in the cut away portions in the disks, and means in the guide for supporting the hangers.

10. In a curtain pole, a guide having a slot in its bottom, a casing in which the guide is disposed and having a slot in its bottom, disks secured to the guide and engaging the inner sides of the casing to hold the guide in position relatively to the casing, the disks having cut away portions from the slot in the guide to the slot in the casing, hangers extending in the slots and in the cut away portions in the disks, means for supporting the hangers, a pulley at one end of the guide and a cord to which a hanger is secured disposed in the cut away portions of the disks and around the pulley.

11. In a curtain pole, a guide with a longitudinal slot in its bottom, a cylinder having a bearing extending through the slot, and bearing means disposed on the bearing

and engaging the inner side of the guide for the purpose specified.

12. In a curtain pole, a hanger having a member with a guideway, a threaded orifice 35 and a clamp, a second member having a guide for moving in the guideway, a guideway and a clamp for coöperating with the first clamp, and a screw disposed in the second guideway and meshing in threaded ori- 40 fice for moving the second member with its clamp relatively to the clamp on the first member.

13. In a curtain pole, a guide having a slot in its bottom, a casing in which the guide 45 is disposed and having a slot in its bottom, disks secured to the guide and engaging the inner sides of the casing to hold the guide in position relatively to the casing, the disks having cut away portions from the slot in the guide to the slot in the casing, a hanger extending in the slots, the hanger having a member with a guideway, a threaded orifice and a clamp, and a second member having a guide for moving in the guideway, a guideway 55 and a clamp for coöperating with the first clamp, and a screw disposed in the second guideway and meshing in threaded ori- fice for moving the second member with its clamp relatively to the clamp on the first 60 member.
